SETTLING CHAMBER FOR SELECTIVE BEVERAGE DISPENSERS

Frederick John Trevallon Barnes,
Brisbane, AustraliaApplication November 28, 1934, Serial No. 755,221
In Great Britain November 28, 1933

6 Claims. (Cl. 225—30)

This invention relates to selective dispensing apparatus whereby any one of a plurality of liquids, or a mixture of a plurality of liquids, can be admitted to, and, if desired, carbonated in, and delivered from a single apparatus.

The various objects and features of the invention will appear hereinafter from the following detailed description of some specific embodiments of the invention illustrated, by way 10 of example, in the accompanying drawing in which:—

Figure 1 is a sectional elevation of a selective dispensing apparatus according to the invention.

Figure 2 is a sectional plan on the line 14—14 15 of Figure 1 and

Figure 3 is a sectional under-plan on the line 15—15 of Figure 1.

The drawing shows an apparatus for dispensing any selected one, or selected mixture, of a 20 plurality of fluids or liquids. A wide cylinder of glass 110 engages a rubber ring 111 at each end; the lower rubber ring 111 is supported in a flanged metal disc 112 resting on another packing ring of rubber 113 engaging the metal body 25 114 of the apparatus. The top rubber ring 111 rests in a flanged metal plate 115 and the plate 115 is connected to the body of the apparatus 114 by vertical tension bolts 116.

It will be seen that the glass cylinder 110 provides a sight chamber which is completely closed except for the inlets and outlets hereinafter mentioned. Depending into the sight chamber are 30 four glass conduits 117 each being received in a union 118 in the top plate 115 and each communicating, as shown in Figure 2, with a lateral branch pipe 119.

The lower end of each glass tube 117 is normally closed by a rubber washer mounted on a conical valve 120 carried on a vertical metal 40 spindle 121, which spindle slides at its upper end through a stuffing-box 122 and is formed with a collar 123 loosely surrounding it and a flanged head 124 fixed to its upper end. A compression-spring 125 engaging the head 124 and the collar 45 123 holds the valve 120 normally closed.

As can be seen from Figures 2 and 3, the axes of the conduits 117 are spaced around the central axis of the sight chamber. Arranged concentrically with the sight chamber is a fixed 50 pillar 126 screw-threaded, as shown, into the top plate 115. Slidably longitudinally on the pillar 126 is a sleeve 127 having a disc-like portion 128 formed integrally with it. The disc 128 is flanged at its under surface to a uniform 55 depth except at a point 129 where a radial en-

largement is formed as can be seen from Figures 1 and 3. The portion 129 is bored to receive a compression-spring 130 acting on a ball 131 adapted to engage with one of four symmetrically arranged grooves 132 in the pillar 126. The 5 bore for the spring 130 is closed by a screw-plug 133.

The sleeve 127 has a head portion 134 screw-threaded onto it and retained by a grub screw 135 and a ring 136 lies loosely around the sleeve 10 between the head 135 and the disc 128.

Projecting upwardly from the top plate 115 of the apparatus is a metal pillar 137 forked at the top to provide a pivot for one end of a lever 138 having a handle at 139. The lever 138 is formed 15 with a ring portion 140 having inwardly projecting screws 141 passing through bosses 142. The pointed inner ends of the screws 141 engage depressions in the ring 136.

From the foregoing description it will be seen 20 that if the handle 139 is moved downwardly the ring 136 engages the disc 128 whereby the disc is also moved downwardly. To limit the extent of movement of the parts a guide pillar 143 is provided diametrically opposite to the pillar 137 25 and is slotted at 144 and the lever 139 passes through this slot. The lever is normally held in the position shown in Figure 1 by a spring 145 engaging a collar 146 on the pillar 126 and abutting against the lower end of the sleeve 127. 30

At the lower end of the apparatus, as shown in Figure 1, a bush 147 is fitted to the body 114 and provides an annular conduit 148 for liquid. Within the bush 147 there is a smaller bush 149 35 which supports a vertical glass tube 150 which rises nearly to the top of the sight chamber.

When the apparatus is in use, each of the branch pipes 119 is connected to a separate source of fluid or liquid. For example, each pipe may communicate with a vessel containing fruit juice, 40 or one of the pipes may be connected to a supply of water for dilution purposes, and another connected to a supply of carbonic acid gas for carbonating the liquid previously admitted to the sight chamber.

The apparatus is operated as follows:—The disc 128 is rotated until the enlarged portion 129 lies immediately above the head 124 of the valve of the conduit appertaining to the particular liquid required. The handle 139 is then pressed 50 down with the result that the particular valve 120 aforesaid is opened by the engagement of the enlarged portion 129 of the disc with the head 124 of that valve, but the other three valves are not opened since the abutment 144 arrests the down- 55

ward movement of the parts before the unenlarged portion of the disc 128 comes into contact with the three remaining valve heads 124. The handle is kept down until the required amount of 5 liquid or fluid has flowed out through the bottom of the tube 117 into the chamber 110. During this operation air from the chamber is exhausted through the glass tube 150 and passes away through shifting ports. If it is desired to mix one 10 fluid or liquid with another, the disc 128 is rotated by means of a knob portion 134 into a new position in which the enlargement 129 engages the head 124 of a different valve. The handle 139 is then pressed down and a different fluid or 15 liquid enters the sight chamber and mixes with the liquid already in it.

To discharge the liquid from the sight chamber 110 a dispensing handle (not shown) is operated which opens a port communicating with the 20 annular conduit 148.

It will be appreciated that the grooves 132 in the pillar 136 are so located with respect to the axes of the conduits 117 that when the ball 131 is in engagement with the groove the enlargement 25 129 is in register with one of the valve heads. The spring 130, the ball 131 and the grooves 132 thus act as a detent to prevent rotation of the disc 126 during the actuation of the handle 139. The disc, or a part attached thereto, may carry an indicator 30 giving the names of the fluids or liquids to which the pipes 119 are connected. An index may be provided on a fixed part of the apparatus to cooperate with the said indicator whereby the appropriate fluid or liquid may be selected by rotating 35 the disc until the name of that fluid or liquid appears opposite the index.

It will be appreciated from the foregoing description that I have provided a simple apparatus for mixing, diluting or carbonating beverages.

40 I claim:—

1. The combination with a transparent walled sight chamber, having an upper wall provided with a plurality of hollow heads, of a plurality of pipes extending downwardly within said chamber 45 from said hollow heads in parallel relationship, valves at the lower ends of said pipes, operating rods attached to said valves, extending within said pipes and through the said hollow heads, heads on the projecting ends of said rods, springs 50 between the second mentioned heads and the upper wall of said chamber, liquid supply conduits admitting to said hollow heads, a stem projecting centrally from said upper wall, a disc rotatable on said stem, a plurality of notches on said stem 55 corresponding in angular position to the several valve rods, spring detent means acting between said disc and said notches, a radial projection on the lower side of said disc, and a hand lever pivotally connected at its end to said sight chamber 60 for vertical movement and engaged with said disc so as to move said disc vertically with said lever.

2. The combination with a transparent walled sight chamber, of a plurality of pipes extending vertically downwardly into said sight chamber 65 and opening near the bottom thereof, valves at the lower ends of said pipes, operating rods for said valves extending outside said sight cham-

ber, a rotatable selector disc having a plurality of setting positions, and a hand lever adapted selectively to operate said valve operating rods through the intermediary of said selector disc.

3. The combination with a transparent walled sight chamber, having an upper wall provided with a plurality of hollow heads, of a plurality of pipes extending downwardly within said chamber from said hollow heads in parallel relationship, valves at the lower ends of said pipes, operating rods attached to said valves extending within said pipes and through the said hollow heads, heads on the projecting ends of said rods, springs between the second mentioned heads and the upper wall of said chamber, liquid supply conduits admitting to said hollow heads, a rotatable selector disc having a plurality of setting positions, and a hand lever adapted selectively to operate said valve operating rods through the intermediary of said selector disc.

4. The combination with a transparent walled sight chamber, having an upper wall provided with a plurality of hollow heads, of a plurality of pipes extending downwardly within said chamber from said hollow heads in parallel relationship, valves at the lower ends of said pipes, operating rods attached to said valves extending within said pipes and through the said hollow heads, liquid supply conduits admitting to said hollow heads, a rotatable selector disc having a plurality of setting positions, and a hand lever adapted selectively to operate said valve operating rods through the intermediary of said selector disc.

5. The combination with a transparent walled sight chamber, having an upper wall provided with a plurality of hollow heads, of a plurality of pipes extending downwardly within said chamber from said hollow heads in parallel relationship, valves at the lower ends of said pipes, spring controlled operating rods attached to said valves and extending within said pipes and through the said hollow heads, liquid supply conduits admitting to said hollow heads, a rotatable selector disc having a plurality of setting positions, and a hand lever adapted selectively to operate said valve operating rods through the intermediary of said selector disc.

6. The combination with a transparent walled sight chamber, having an upper wall provided with a plurality of hollow heads, of a plurality of pipes extending downwardly within said chamber from said hollow heads in parallel relationship, valves at the lower ends of said pipes, spring controlled operating rods attached to said valves, and extending within said pipes and through the said hollow heads, liquid supply conduits admitting to said hollow heads, a stem projecting centrally from said upper wall, a disc rotatable on said stem, a plurality of notches in said stem corresponding in angular position to the several valve rods, spring detent means acting between said disc and said notches, a radial projection on the lower side of said disc, and a hand lever pivotally connected at its end to said sight chamber for vertical movement and engaged with said disc so as to move said disc vertically with said lever.

FREDERICK JOHN TREVALLOON BARNES.
